MICROMETER OR THE LIKE

Application filed May 16, 1927. Serial No. 191,624.

This invention relates to improvements in micrometers, or the like.

In the use of micrometers and other gauging and measuring instruments designed for 5 very accurate work, errors frequently arise due to the inability of the user to read accurately the necessarily fine graduations provided. These errors result, not from a lack of a correct understanding of the use of the 10 instruments, but to the fact that the light reflection from the graduated area is often such as to render the graduations obscure.

The object of the present invention therefore is to remedy this defect by providing an 15 instrument, the graduations or scales of which are visually distinct from the background thereof. This improvement is effected by treating those areas of the instrument, which include the graduations, so as to render the 20 areas dull in appearance, thereby enhancing the visibility of the graduations and reducing the likelihood of errors in the use of the device.

In the accompanying drawing, a micrometer embodying the present invention is illustrated. The micrometer may be of standard construction and will not be described in detail, and, as shown in the drawing, may have two sets of graduations 10 and 11, the 30 former being on the member 12 and the latter on the rotatable sleeve 13. The backgrounds of the graduations are treated to dull the surfaces thereof, as indicated at 14 and 15 in the drawing, which treated surfaces 35 may be as extensive as desired and may include in some instances the usual figures associated with the graduations. The dulled or non-reflecting surface of the sleeve 13 is shown extended sufficiently to include the 40 figures, although the figures may be placed outside of and adjacent the treated surface, as shown at 10, if desired.

The preferred method of treating the graduated portions of the instrument to obtain 45 this desired result is by etching, although sand blasting or other methods may be used, the technique of which methods will not be described herein.

In micrometers and related gauging or 50 measuring instruments the scales or gradu-

ations are generally formed by a rolling operation, and when they are subsequently heat treated for tempering, the graduations become somewhat darker in appearance, and stand out distinctly on the dull background 55 above described.

Although I have illustrated one embodiment of my invention for the purpose of illustration, it will be understood that I do not wish to be restricted to the form shown, 60 except where limitations thereto appear in the appended claims.

What I claim new is:

1. A micrometer having graduations thereon, the graduations and the background 65 thereof being treated to dull the same to thereby accentuate the visibility of said graduations.

2. A micrometer having graduations thereon, a portion of the surface thereof including 70 said graduations being etched to provide a dull surface for the purpose of enhancing the visibility of said graduations.

In testimony whereof I have subscribed 75 my name.

ERIK G. PEHRSSON.
